JOHN C. ZWART AND GERRIT C. ZWART, OF GLENBROOK, CONNECTICUT.

RAIL-CLAMP.

1,381,955.

Specification of Letters Patent. Patented June 21, 1921.

Application filed March 14, 1921. Serial No. 452,100.

To all whom it may concern:

Be it known that we, JOHN C. ZWART and GERRIT C. ZWART, citizens of the United States, residing at Glenbrook, county of 5 Fairfield, State of Connecticut, have invented an Improvement in Rail-Clamps, of which the following is a specification.

This invention has for its object to provide clamps for railroad use which shall be 10 inexpensive to produce, very strong, easily operated, and which will securely lock the rails to the ties and wholly prevent creeping of the rails, and will avoid injury to the ties by spikes, screws, etc. Each rail 15 clamp comprises a pair of flange clamps having interlocking shanks, a base plate, and a bolt which passes through one of the flange clamps and through the shank of the other flange clamp and engages the base plate.

20 In the accompanying drawings, forming a part of this specification,

Figure 1 is a view showing a rail in cross section, and a tie and our novel rail clamp in elevation;

25 Fig. 2, a view as seen from the right in Fig. 1, the rail and one clamp being in elevation and the tie in cross section.

Fig. 3, a plan view corresponding with Fig. 1, the rail being in section on the line 30 3—3, looking down; and

Fig. 4 is a detail sectional view on the line 4—4 in Fig. 1, looking in the direction of the arrows.

10 denotes a rail and 11 a tie. Our novel 35 rail clamp comprises flange clamps 12 and 13 which engage the respective flanges of the rail. Each clamp comprises an upper and lower jaw, the operative faces of which correspond with and are adapted to engage

40 the upper and lower sides of the rail flange. We have shown these jaws as provided with engaging ribs 14 which bear on the respective surfaces of the rail flanges. These ribs may or may not be used as preferred. It

45 will be noted that the space between the engaging flanges at the bases of the jaws is slightly less than the thickness of the flanges at the edge. This is in order to provide for variation, within reasonable limits, in the

50 thickness of the flanges and to insure locking engagement of the jaws with the flanges at all times. Flange clamp 12 is provided with an outwardly extending lug 15 through which the bolt 16 passes obliquely to the 55 vertical plane of the rail. Flange clamp 12 is furthermore provided with a shank 17

which likewise extends downward obliquely to the vertical plane of the rail. Flange clamp 13 is provided with a shank 18 which extends downward obliquely, crossing the 60 plane of the shank of clamp 12. Shanks 17 and 18 are made interlocking by means of a relatively wide rib 19 on shank 18, which engages a corresponding groove 20 in shank 17. The connection is loose enough to permit sliding movement of the shanks relatively to each other, as will presently be explained. The lower end of the bolt is shown as reduced, the reduced end passing through the lower end of shank 18 which is shown as 70 enlarged to give greater strength. A shoulder 21 on the bolt engages the upper side of said shank.

22 denotes the base plate which extends transversely under the tie and is made 75 enough longer than the width of the tie to provide engaging ends 23 to receive the ends of the bolts on opposite sides of the tie. The base plate is preferably provided with longitudinal ribs 24 as shown, or engaging 80 points if preferred, which are forced into the under side of the tie to prevent movement of the plate. The base plate is also provided with bosses 25 to provide additional engaging surface for the threads of the bolts, the 85 ends of the plates and the bosses being provided with threaded holes, which are engaged by the lower ends of the bolts.

Our novel rail clamps are used in pairs, 90 one being placed on each side of every tie. The position of the rail clamps is reversed so that the heads of the bolts lie on opposite sides of the rail and the bolts extend downward and inward obliquely, i. e., toward each other from the lugs 15 to the 95 base plate, as will be understood from Figs. 1 and 3. When a bolt is screwed down, shoulder 21, bearing on shank 18, will draw flange clamp 13 inward and downward and, through the interlocking engagement of shank 18 with shank 17, will draw clamp 12 also inward and downward. We thus force the jaws of both flange clamps inward tightly upon the flanges and also draw the rail down tightly upon the tie. The structure as a whole is thus made firm and rigid and creeping of the rail is prevented.

Having thus described our invention, we claim:

1. A rail clamp comprising flange clamps 110 for the flanges of a rail, said clamps having inwardly and downwardly extending in-

terlocking shanks and one of said clamps having an outwardly extending lug, a bolt extending obliquely downward and inward and passing through said lug and through 5 the shank of the other clamp, and a base plate engaged by said bolt.

2. A rail clamp comprising flange clamps for the flanges of a rail, each flange clamp consisting of jaws adapted to engage the 10 opposite sides of a rail flange and each having a downwardly and inwardly extending shank interlocking with the shank of the other clamp, a bolt engaging one flange clamp and the shank of the other flange clamp, and a base plate engaged by the bolt.

3. A rail clamp comprising flange clamps for the flanges of a rail, said clamps having downwardly and inwardly extending interlocking shanks and one of said shanks 20 having an outwardly extending lug, a bolt extending through said lug and through the shank of the other flange clamp and having a shoulder bearing on said shank, and a base plate engaged by said bolt, tightening 25 of the bolt through the engagement of said shoulder and said shank acting to draw the

flange clamps inward on the rail flanges and to draw the rail downward against the tie.

4. A rail clamp comprising flange clamps having interlocking shanks, and means 30 engaging one flange clamp and the shank of the other flange clamp for simultaneously forcing said flange clamps inward and downward.

5. A rail clamp comprising flange clamps 35 provided with interlocking shanks, a bolt passing through one flange clamp and having a shoulder engaging the shank of the other flange clamp, and a base plate engaged by said bolt.

6. A rail clamp comprising flange clamps having upper and lower jaws provided with engaging ribs, said flange clamps having shanks which interlock, a bolt passing through one flange clamp and engaging the 45 shank of the other flange clamp, and a base plate engaged by the bolt.

In testimony whereof we affix our signatures.

JOHN C. ZWART.
GERRIT C. ZWART.
